UNITED STATES PATENT OFFICE.

HENRY K. SWINSCOE, OF CLINTON, MASSACHUSETTS.

WIRE-NETTING MACHINE.

SPECIFICATION forming part of Letters Patent No. 483,182, dated September 27, 1892.

Application filed November 16, 1891. Serial No. 412,065. (No model.)

To all whom it may concern:

Be it known that I, HENRY K. SWINSCOE, of Clinton, county of Worcester, State of Massachusetts, have invented an Improvement in 5 Wire-Netting Machines, of which the following description, in connection with the accompanying drawings, is a specification, like letters and figures on the drawings representing like parts.

10 In my experiments to cheapen the cost of production of netting for fencing, &c., without lessening its practical value I have devised a machine having two independently-actuated racks which may be moved for different distances, thereby enabling the twisting-segments containing the wires for the main body of the netting and rotated by one of the racks to be rotated twice, while the segments carrying the selvage-wires and the segments 15 having wires which are to be wrapped or twisted about the selvage-wires may be rotated three or, it may be, more times by the other rack, thus producing a netting having its body-wires united by a different number 20 of twists than are its selvage-wires.

25 One part of my invention therefore consists in a wire-netting machine containing the following instrumentalities, viz: sliding carriages, a series of twisting segments carried by said carriages, actuating devices for some of the said segments, and independent separate actuating devices disconnected therefrom for other of the said twisting-segments, whereby some of the segments may be rotated independently 30 of other of the said segments, as will be described.

35 Other features of my invention will be more specifically described, and pointed out in the claims at the end of this specification.

40 Figure 1 in front elevation, partially broken out, shows a sufficient portion of a wire-netting machine with my improvements added to enable my invention to be understood; Fig. 2, a right-hand end view thereof; Fig. 3, 45 a longitudinal section in about the line x , Fig. 1, showing parts of the sliding carriages, some of the twisting-segments, and the two racks, part of the top rack being broken out to show the under rack below it. Fig. 4 shows 50 the opposite ends of the inner edge of the back carriage and some of the pairs of twisting-segments. Fig. 5 is a view similar to Fig.

3, but with the carriages and racks in their opposite strokes; and Fig. 6 is a view of Fig. 5, similar to Fig. 4.

55 The framework A, the mesh-roll B, the take-up roll C, and the carriages D E, connected by a lever F, pivoted on a stand F', are and may be all substantially as usual in wire-netting machines, the contiguous faces of the said carriages containing notches for the reception of twisting-segments to be described.

60 The twisting-segments ordinarily used with sliding carriages such as shown are toothed just alike, and commonly the said teeth are 65 from bottom to top, filling the space between the upper and lower walls of the carriages; but in some instances the said segments have had teeth on their shanks for but a portion of their length; but in such cases the lower 70 sides of the projections having the teeth have rested on the lower part of the carriages and all the teeth have been in the same horizontal plane, so that one and the same rack might rotate all the said segments.

75 In devising my improved machine for the manufacture of my novel wire-netting I have had to depart from heretofore usual constructions and have provided some of the twisting-segments with teeth occupying a different 80 horizontal plane from the teeth of the other segments, I in the present form of my invention having provided the segments *a* of the front and back carriages—viz, the segments which carry the wires used in the body of the 85 netting and not twisting with the selvage-wire—with teeth *2*, which occupy a position close to the bottom part of the sliding carriages. Others of these segments, especially the two segments *b* *b'*, which carry body-wires and 90 which are located near the ends of the series of segments *a* *a*, one of the segments *b* being in one carriage when the other segment *b'* is in the other carriage, and the selvage-carrying segments *c* and *c'* and the dummy-segment (marked *d*) will have their teeth *3* in 95 a different horizontal plane from that occupied by the teeth *2*, so that one rack, as the under one *e*, may engage the teeth *2* of the segments *a*, while the teeth *3* in the segments *b*, *b'*, *c*, *c'*, and *d* are shown as located at a higher 100 level, so as to be engaged by the teeth of the rack *f*, lying, as shown, on the rack *e*. All the segments carried normally by the front

carriage D, with the exception of segment c, will have connected to their lower ends suitable tubes g, which will contain cops of wire, the said tubes being of common construction. 5 All the segments in the back carriage, with the exception of the segment b, are or may be supplied with wire from suitable spools h; but the segment b must have a tube, provided the selvage-segments c and c' are supplied 10 with wire 3 4, as is usually the case with wires taken from bobbins or spools c² c². The rack e is shown as joined by a link e' to a rack-operating device, shown as a lever pivoted at e³. The rack f is shown as joined by a link f' to a rack-operating device f², shown as a lever pivoted at f³.

The rack-operating devices represented are of the simplest form known to me; but in practice it will be understood that I may, instead of the devices shown, employ any other usual or suitable actuating devices for the said racks so long as they are so made or constructed as to enable the said racks to be reciprocated different distances and at the same 25 or different times, it being understood that to do this the actuating devices to turn the segments more or less are and must be disconnected from each other. The front carriage D is joined by link m to a lever m', so that 30 as said lever is moved, in this instance by hand, the two carriages will be moved simultaneously in opposite directions. Instead, however, of the hand-lever as an operating device for the said carriages, the carriage D 35 may be actuated in any usual or suitable manner.

In Figs. 1, 3, and 5 I have omitted from the central part of the carriages some of the segments a. Let it be assumed that all the segments except the dummy d have wires, the two segments c and c' having selvage-wires. Figs. 1 and 3 show the front carriage as moved 40 fully to the left, together with both racks, and the selvage-segment c opposite the dummy d 45 and segment c' in the back carriage. In this condition the front carriage by the operative device m' will be moved to the right, and the segments carried thereby will assume the positions shown in Fig. 5. Then both racks will 50 be moved to the right, and in so doing all the segments will be rotated; but by moving the rack f farther than the rack e it results that the segments c and b, as one pair at the left in Fig. 5, and the segments c' and b' at the 55 right, as another pair, are twisted a greater number of times, so that if two twists are given to the segments a three twists or more, if desired, may be given to the segments c b c' b'. This done, the carriage D will be shifted 60 to the left, putting the segments in the position Fig. 3, the racks e and f moving to the left on the carriage D. Then in that position of the segments the racks e and f will be moved to the right, but this time for equal distances, so as to put into the wires two twists. 65 At this time it will be noticed that the twisting-segment c is opposite the dummy d, which

is like the segment c, only that it has not a wire, and that the segment c' is standing by itself and the segments b and b' are opposed to segments a. In this position the selvage-wires are not twisted with any other wire. After this the carriage D is again shifted to the right into the position Fig. 5; but at this third stroke the two racks e and f, instead of being shifted to the right, as before described, are shifted to the left and the rack f for the greater distance, so as to rotate the segments c and b and c' and b' one or more times more than the segments a a. The carriage D is next 70 slid to the left, carrying with it the racks e and f, putting the segments again in the positions shown in Fig. 3, and the racks are again moved to the left, but only far enough to rotate all the segments twice. The next movement 75 will be a repetition of the first of the four movements just described.

The mesh-roll B may be actuated in any usual way to take up the wire-netting as produced, and as fast as made the netting will 80 be wound on the take-up roll C.

My invention may be applied to machines capable of putting reverse twists into the meshes, the machine in such case containing suitable clamping devices—as, for instance, 95 such as provided in United States Patent No. 387,739, dated August 14, 1888, and granted to B. Scarles—and in this latter instance, owing to the fact that the segments c and b and c' and b' may be moved independent of 100 the body-wire segments a, I may, if desired, unite the selvage-wire to the body-wire by a series of twists in one direction and unite the body-wires by a series of reverse twists.

In my application, Serial No. 393,608, filed 105 May 21, 1891, I show a wire-netting machine containing main and auxiliary carriages, each having its own proper segments, and the said segments are each actuated by its own proper rack, and it is obvious that I might apply my 110 present invention to the machine shown in said application and put more twists into the meshes at one side than into the meshes at the other side of the same row of meshes—as, for instance, more twists into the wide-mesh 115 part of the fabric than into the narrow-mesh part of the fabric. So, also, it is obvious that by collecting at one end of the pair of carriages segments like a and at the other end segments like those marked b b' c c' I might 120 make a fabric in which the twists at one part of one row of meshes might have, say, two twists and the other parts three twists.

The particular means for moving the segments are, as herein shown, rack-bars; but 125 instead of these rack-bars I might use any other suitable moving device adapted to engage and rotate the selvage-segments independently of the body-segments, and thus impart to each of the said segments greater or 130 less motion, as desired.

I am aware that it has been proposed in a machine to put less twist into the wires carried by the segments containing the selvage-

wires than in the wires carried by the segments provided for producing the body of the fabric; but in such plan the segments containing the body-wires were actuated by toothed surfaces connected directly with and receiving their motion from the lever or device which actuates the toothed surfaces for rotating the segments containing the body-wires, and hence in such plan the movements were not independent, although some of the segments were rotated more than others.

This invention is not limited to the exact form of twisting device for uniting the parallel wires nor to the particular means shown to support the said twisting devices in order that the wires may be twisted alternately with each other.

The selvage-wires are commonly larger than the body-wires with which they are united in the production of netting, and hence the selvage and body wires do not twist alike when being united; but on the contrary the selvage-wire remains substantially straight and substantially all the twist appears in the body-wire, and that wire is wrapped, as it were, about the selvage-wire, and consequently the netting made from the body-wire slips on the selvage-wires and destroys the symmetry of the meshes. To overcome this slipping, I have, as stated, devised a machine to put more twist at the selvage than at the mesh joining. The additional friction due to a greater number of twists of the body-wire about the selvage-wire produces a joint which will not slip; and the number of extra twists may, it is obvious, be increased as desired, provided the mesh is of proper length.

Having described my invention, what I claim, and desire to secure by Letters Patent, is—

1. In a machine for the production of wire-netting, the following instrumentalities, viz: sliding carriages, a series of twisting-segments carried by said carriages, actuating devices for some of the said twisting-segments, and independent separate actuating devices disconnected therefrom for others of the said twisting-segments, whereby some of the segments may be rotated independently of the other of the said segments and in different

directions to form reverse twists, substantially as described.

2. In a machine for the production of wire-netting, the following instrumentalities, viz: sliding carriages, a series of twisting-segments 55 for the body-wires and twisting-segments for the selvage-wires, carried by the said carriages, actuating devices for the segments, containing the body-wires, and separate independent actuating devices for the remaining or selvage-wire segments, said latter actuating devices being disconnected from the actuating devices for the body-wire segments, whereby the travel of each of said actuating devices may be varied independently and one series 65 of the said segments may be rotated more than the other series of said segments, substantially as and for the purpose described.

3. A wire-netting machine containing the following instrumentalities, viz: a series of 70 twisting devices for the wires to be twisted together in the production of the netting, the gears of one of the said series of twisting devices being in a different horizontal plane from the gears of the other of the said series 75 of twisting devices, supports for the said twisting devices, and independent rack-bars, one for actuating one of the said series of twisting devices and the other to actuate the other of the said series of twisting devices, and 80 disconnected mechanism to move each of the said rack-bars independently one of the other in either the same or opposite directions, substantially as described.

4. In a wire-netting machine, shifting carriages provided with a series of twisting-segments mounted therein, combined with two independent rack-bars having their teeth in different horizontal planes and separate and disconnected means to actuate the said rack-bars to rotate some or others of the said twisting-segments, as desired, and for the purposes set forth.

In testimony whereof I have signed my name to this specification in the presence of 95 two subscribing witnesses.

HENRY K. SWINSCOE.
